(57) CLAIM

The ornamental design for a tray for smoking accessories storage and preparing herbal mixtures, as shown and described.

DESCRIPTION

FIG. 1 is a front perspective view showing my new design of a tray for smoking accessories storage and preparing herbal mixtures;

FIG. 2 is a front side view of the tray for smoking accessories storage and preparing herbal mixtures;

FIG. 3 is a rear side view of the tray for smoking accessories storage and preparing herbal mixtures;

FIG. 4 is a left side view of the tray for smoking accessories storage and preparing herbal mixtures;

FIG. 5 is a right side view of the tray for smoking accessories storage and preparing herbal mixtures;

FIG. 6 is a top side view of the tray for smoking accessories storage and preparing herbal mixtures; and,

FIG. 7 is a bottom side view of the tray for smoking accessories storage and preparing herbal mixtures.

The broken lines in the drawings depict portions of the tray for smoking accessories storage and preparation of herbal mixtures that form no part of the claimed design.
